UNITED STATES PATENT OFFICE.

WILLIAM V. SUTTON, OF ROCKFORD, ILLINOIS, ASSIGNOR TO SUTTON SHOPS, INC.,
OF ROCKFORD, ILLINOIS, A CORPORATION OF ILLINOIS.

CAP.

Application filed February 5, 1927. Serial No. 166,049.

This invention relates to caps and, more particularly, skeleton or visor caps such as are used for general outdoor and sporting use.

5 The principal object is to provide an adjustable head band on caps of the kind referred to so as to make it possible for the purchaser to adjust the size of the cap to his particular requirements. This provision obviates the necessity for carrying many different sizes of caps in stock, and also avoids the necessity for providing the unsightly elastic at the back of the head band, which was otherwise ordinarily provided to accommodate minor variations in size, and which aside from its unsightly appearance, was also objectionable from the standpoint of placing an uncomfortable tension on the head band, oftentimes sufficient to cause a 20 headache.

According to the present invention the end portions of the band at the back of the cap are provided with clips for holding the same in variable degrees of overlapping relation to accordingly adjust the size of the cap, the clips being frictionally slidable on the end portions of the band so that it is a simple matter to make the desired adjustment, and the end portions of the band will 25 be held relatively securely in their adjusted position. The cap is therefore very comfortable to wear and gives entire satisfaction, and has been found to be much preferred to the previous type. Furthermore, the overlapping of the end portions of the band avoids the patch-work appearance which was otherwise produced when an elastic, of contrasting appearance, had to be sewed in between the ends of the head band. The appearance of the cap is therefore greatly improved.

40 The invention illustrated in the accompanying drawing wherein Fig. 1 is a perspective view of a cap embodying my invention.

Fig. 2 is an enlarged sectional detail taken on the line 2—2 of Fig. 1, showing one of the clips fastened on one end portion of the band and slidable on the other end portion.

45 Fig. 3 is an inside view of the band indicating in dotted lines the manner of adjustment.

Fig. 4 is a plan view of Fig. 3 further indicating in dotted lines the adjustability.

55 Fig. 5 is a perspective view of one of the

clips previous to the fastening thereof on the free end portion of the band.

Fig. 6 is a view showing the clip fastened on the band to indicate how the raw end of the band is concealed in the clip and is securely fastened thereto, the way in which the clip is formed after this stage so as to be slidable on the other end portion of the band being illustrated in Figs. 2 and 3.

60 The same reference numerals are applied to corresponding parts throughout the views.

65 The invention is herein illustrated as applied to a skeleton or visor cap consisting of a visor 10, head strap or band 11, and crown strap or band 12. The particular design of

70 cap shown is intended for ladies' wear and has the head band 11 conformed with an arch front as indicated at 13 to give a coronet effect. In keeping with the disclosure in the Sutton Patent #1,599,978 issued September 14, 1926, the visor, head band, and crown strap are formed of pieces of celluloid

75 cut to shape and bound about the edges with a pliable binding material indicated at 14. The parts are sewed together by stitching indicated at 15 which passes through the celluloid and binding material of the joining parts.

80 In the present case a sweat band 16 inserted in the fold of the binding material on the lower edge portion of the head band, together with ends of the crown strap 12.

85 the sweat band and crown strap being sewed together to the head band by the stitching fastening the binding material to the head band.

90 For the purpose of providing a more secure fastening of the crown strap the latter is preferably of increased width at the ends, as shown at 17. This much description will suffice to give an impression of the kind of

95 cap to which the invention is particularly intended to be applied. The present invention provides adjustability as to size in the head band 11 at the back thereof as indicated at 18 by enabling the overlapping of the free ends of the head band to variable degrees.

100 The purpose in this is to enable the purchaser to adjust the size of the cap to suit his particular requirements and to make it unnecessary for the jobber to carry in stock many different sizes of caps. In the past the matter of size was taken care of by providing

105 several sizes of caps having elastics sewed in the band at the back, or elsewhere, so that the head band could be stretched to accommodate such minor variations in size as

110

might be desired. The objection to this solution of the problem, aside from the fact that it necessitated carrying a number of sizes of caps in stock, was that the elastic 5 gave a patch-work appearance to the cap by reason of its contrast to the design of the head band of the cap, but more important still, the elastic when stretched placed an uncomfortable tension on the head band which 10 in many cases gave the wearer a headache. These objectionable features are avoided by the present invention as the cap, provided with an adjustable head band in accordance with my invention, can be adjusted to the 15 exact size required by the purchaser, and the cap, when so adjusted, will be comfortable to wear and will give generally better satisfaction. Furthermore, the continuity in design of the head band is not broken since the ends 20 of the head band are overlapped. The cap, therefore, has a much better appearance and, in fact, it has been found to be much preferred to the old type.

Referring now more particularly to Figs. 25 2 to 6 for a detailed description of the adjustment, it will be observed that each of the end portions of the head band has a clip 20 fixed to the end thereof and slidably engaging the other end portion of the band 30 while holding the end portions in overlapping relation. The ends of the head band are therefore capable of being overlapped to variable degrees to correspondingly adjust the over-all length of the band. The 35 way in which the clips are brought together in the expansion of the band or separated in the contraction of the band is believed to be clear from the dotted line and full line positions of the parts illustrated in Figs. 40 3 and 4. Each of the clips is preferably formed of sheet metal from a struck out blank strip. The strip, as shown in Fig. 5, has one end portion thereof bent longitudinally as indicated at 21 to provide a clamp 45 22, in the recess 23 of which the raw or unfinished end of the head band may be inserted and thus effectively concealed as indicated in Fig. 6. This construction makes 50 for a neat and workmanlike appearing cap. The clamp is closed on the band and suitably punched at a number of points as indicated at 24 so as to insure the gripping of 55 the clip on the band. The remaining end portion of the blank strip, designated by the reference numeral 25, is arranged to be bent, 60 as shown at 26 in Fig. 2, alongside the first end portion about the other end portion of the head band so as to hold the two end portions of the head band in overlapping 65 relation, with the clip on each end portion of the band slidable on the other end portion thereof in a manner believed to be apparent. The free end of the blank strip 70 is then bent, as indicated at 27 in Fig. 2, so as to keep the overlapped end portions of

the band in edge to edge alignment. It is preferred to cut away one wall of the clamp 75 22 in a stepped fashion, as indicated at 28, and to correspondingly form the other end of the blank strip in a stepped fashion, as indicated at 29, to match the same when the blank is bent to complete the form of clip appearing in Figs. 2 and 3. The edge of the head band at the bend 27 is thereby neatly confined in the clip and the clips will slide 80 on the head band with little difficulty, there being only sufficient friction developed to keep the head band in any state of adjustment. The band will not enlarge in the ordinary wearing of the cap, but if it should tend to the clips may be closed a little more tightly to increase the frictional resistance to spreading. It is obvious that the two 85 clips will be disposed in reverse relation to one another when fastened on the opposite ends of the head band since the clamp portion 22, by means of which the clips are fastened to the ends of the head band, determines the position of the clip. By reason 90 of this fact only one of the stepped joints 28-29 will be exposed at the back of the cap. However, the joint is practically closed when the clamp is properly secured to the head band and it is found that the joint in the clip does not detract from the appearance 95 of the cap to any appreciable degree.

I claim:

1. In a size adjustment for caps and the like, means for holding a pair of strap ends in variable degrees of overlapping relation, the said means comprising a metallic clip fixed on one of the strap ends, said clip being formed from a strip of sheet metal bent longitudinally of one end portion thereof to fit over the raw end of the strap, the bent portion being closed on the strap end to clamp the same and conceal the raw end thereof, and the other end portion of said strip being bent alongside the first end portion thereof about the other strap portion of the band whereby to hold the strap ends in overlapping relation.

2. In a size adjustment for caps and the like, means for holding a pair of strap ends in variable degrees of overlapping relation, the said means comprising a metallic clip fixed on one of the strap ends, said clip being formed from a strip of sheet metal bent longitudinally of one end portion thereof to fit over the raw end of the strap, the bent portion being closed on the free end of the strap to clamp the same and conceal the raw end thereof, the other end portion of the strip being bent alongside the first end portion thereof about the other strap and having its free end bent around the other free end of the strip whereby to hold the clip against opening.

3. In a size adjustment for caps and the like, means for holding a pair of strap ends

in variable degrees of overlapping relation, the said means comprising a metallic clip fixed on one of the strap ends, said clip being formed from a strip of sheet metal bent 5 longitudinally of one end portion thereof to fit over the raw end of the strap, the bent portion being closed on the free end of the strap to clamp the same and conceal the raw end thereof, the other end portion of 10 the strip being bent alongside the first end portion thereof about the other strap and having its free end bent around the other free end of the strip and arranged to interlock therewith whereby to hold the clip 15 against opening.

4. In a size adjustment for caps and the like, means for holding a pair of strap ends in variable degrees of overlapping relation, the said means comprising a metallic clip 20 fixed on one of the strap ends, said clip being formed from a strip of sheet metal bent longitudinally of one end portion thereof to fit over the raw end of the strap, the bent portion being closed on the free end of the 25 strap to clamp the same and conceal the

raw end thereof, the other end portion of the strip being bent alongside the first end portion thereof about the other strap and having its free end bent around to interlock with the other free end of the strip, the said 30 free ends being notched out so that the one free end fits in the other free end, thus tending to hold the clip against opening.

5. In a size adjustment for caps and the like, means for holding a pair of strap ends 35 in variable degrees of overlapping relation, the said means comprising a clip fixed on one of the strap ends, said clip being formed from a single strip of material having one end portion bent to overlap the raw end of 40 the strap, the said bent portion being closed on the strap end to clamp the same and conceal the said raw end, the other end portion of the strip being bent to pass around the other strap whereby to hold the strap ends 45 in overlapping relation.

In witness of the foregoing I affix my signature.

WILLIAM V. SUTTON.
